APPLICATOR

Oreste R. Scioscia, Pittsburgh, Pa.

Application January 25, 1941, Serial No. 376,003

5 Claims. (Cl. 15—140.3)

This invention relates to applicators and has particular relation to such an applicator as may be used for removing small portions of liquid from a dish or bottle.

In the past it has been common practice to use applicators but many of these have certain objectionable features which are eliminated in the present invention.

The primary object of the present invention is to provide an improved applicator.

Another object of the invention is the provision of an applicator which will hold liquid and will immediately discharge the same when it is desired.

Still another object of the invention is the provision of an applicator which when being used, does not have to actually touch the body to which it is being applied in order to discharge the liquid.

Still another object of the invention is the provision of an applicator which will pick up a uniform and substantial amount of liquid and which is easily discharged when desired.

Another and still further object of the invention is the provision of an applicator which will remove practically the last drop of the liquid from a bottle and when being drawn out therefrom, less care is necessary in avoiding touching the sides of the bottle.

Other and further objects of the invention will be apparent to those skilled in the art from a reading of the complete specification and claims.

Referring to the drawings wherein I have illustrated embodiments of my invention,

Fig. 1 shows the applicator in a bottle of the cork type, the latter being partially sectioned for the purpose of clearness;

Fig. 2 is another form of the invention as applied to a screw-type closure member of a bottle, the bottle being sectioned for clearness;

Fig. 3 is a view of my invention similar to Fig. 2 but in a different position.

Figs. 4, 4a, 5 and 6 illustrate modifications of the invention.

Fig. 7 is a modification of the form of the invention illustrated in Fig. 6.

Similar reference characters refer to the same or similar parts throughout the specification and drawings.

In providing my improved applicator, I utilize the surface tension of the liquid to be applied, to hold the same in position in the applicator. In addition to this, there is provided a construction which will withdraw practically the last drop from the bottle space and deliver it to the applicator at its delivery end.

Referring to the drawings, wherein is illustrated my invention, 10 designates the bottle wherein a cork-type top applicator is illustrated. The applicator comprises a cork stopper 11 having a knob 12 suitably secured thereto. The cork stopper has a cylindrical opening centrally located in which is installed an applicator tube 13. The tube 13 is supplied with an opening 13a at its bottom end. The tube opening 13a is of a size to provide support for the particular liquid to be dispensed considering the characteristics of that liquid.

The applicator tube 13 is also provided with a second opening 13b. This opening 13b preferably extends from a point slightly above the bottom of the cork stopper to a point below the bottom of the cork stopper to permit the liquid to enter the tube.

In Figs. 2 and 3 is illustrated a slight modification of the invention. In this form a bottle 110 has an outside threaded top and is provided with a composition interiorly threaded stopper 111 having a knob 112 preferably integral therewith. An applicator tube 113 is preferably embedded in the composition of the stopper 111 when it is soft thus not displacing the surface 111a within the tube as clearly shown in Fig. 2. An opening 113a is provided in the lower end of the applicator tube 113 from which the liquid is dispensed. Another opening 113b is provided in the tube 113 adjacent the lower surface of the stopper 111, as shown in Figs. 2 and 3.

In operation, when the bottle is full or contains a substantial amount of liquid, it is only necessary to shake the bottle to get a sufficient amount of liquid in the applicator tube through the opening 13b or 113b. Upon removal of the applicator, the opening 13a or 113a is sufficiently small to permit the liquid to hold on and in the applicator until applied to the surface to be moistened. The opening then gives up the liquid as needed.

It is when the bottle is half or nearly empty of fluid that the great advantage of the present invention is apparent. Let us assume the liquid present in the bottle to be only a few drops. The user upon observing this fact, inverts the bottle so that the liquid is supported by the stopper. By a slight shake, the liquid will enter the opening 13b or 113b, any air displaced, escaping through the opening 13a or 113a.

By now restoring the bottle to upright position, the liquid will pass down the sides of the tube 13 or 113 to the dispensing opening 13a or 113a. The user now removes the applicator and

applies the liquid as desired in the usual manner. As the liquid leaves at the dispensing opening 13a or 113a, air enters the opening 13b or 113b.

The essential difference between the structures of Figs. 1 and 2, as far as operation is concerned, is in the space above the opening 13b in Fig. 1 and the lack of it in Fig. 2. However, both forms of construction operate very well. By having the collecting surface provided by the bottom of the stopper, when inverted, it will clearly be seen that all of the liquid, except that which adheres to the bottle walls will be removed during normal operation and use.

In Figs. 4 and 4a I illustrate a form wherein the stopper top and a holding cylinder may be constructed of any suitable material, such as Bakelite, the applicator means comprising a portion 212 integral with the closure member or stopper 211 and a lower portion, which actually applies the liquid, fits snugly in the upper portion. The portion 212 has a split 212a which extends substantially to the under surface of the stopper or closure member 211.

An applicator tube 213 which, if desirable, may be provided with a split 213a, has an outside diameter which is a forced fit with the inside diameter of the holding cylinder 212. This applicator tube may be made of glass, Bakelite or any other suitable material.

In assembling the parts it is only necessary to force the applicator tube 213 into the holding cylinder 212 so that the split 213a, if provided, does not register with the split 212a. This applicator tube is forced in, only, to a point where there is still an opening through the split 212a over the top edge of the applicator tube 213. This opening at 214 corresponds with the openings 13b and 113b already described.

If desired, the tube 213 with its split 213a may be used with the stopper 11 as illustrated in Fig. 1.

In Fig. 5 I have illustrated an applicator wherein in the stopper member 311 and the dispensing tube 312 are turned or cast and integral with each other. In such a construction, the opening 314 located adjacent the lower wall of the stopper 313 and the opening 313 are formed during the casting operation. To close the opening at the top of the tube 312, the grip member or handle 315 is secured in place as shown on Fig. 5.

In Fig. 6, I illustrate a stopper or closure member 411 having an integral applicator means 412. The applicator means has an opening 412a at its lower end and an opening 414 at the upper end at the surface of the closure member.

In constructing this modification of the invention I would preferably make it of a castable or plastic material, the applicator means 412 being made first cylindrical and then by a suit-

able tool with heat if necessary, nearly closed at its lower end. The opening 414 could be made by a drill or by any suitable means.

In Fig. 7, is illustrated a further modification 5 of the invention. The closure member 511 has an extending cylindrical portion 512 which is provided with an opening 512a. On the outside of the extension 512 is a tip portion 513 having an inside diameter to fit the outside diameter 10 of the extension 512. This tip portion 513 is provided with an opening 513a at its lower end. In this form the extension 512 and the tip 513 together form the hollow applicator means. The tip portion 513 may be made of hard or soft 15 rubber or any other suitable material.

While I have illustrated and described my invention in detail, it is to be understood that the details of the disclosure are merely illustrative and that modifications and changes may be made 20 within the scope of, and without departing from the spirit of, the invention, as claimed.

Having described my invention what I claim is:

1. An applicator comprising a closure member 25 formed with a concave lower surface, hollow applicator means extending from the inner surface of the closure member, the hollow means having an opening adjacent its lower end and a second opening at the crown of the lower surface of the closure member.

30 2. An applicator comprising a closure member formed with a concave lower surface, a tubular applicator means including a hollow portion integral with the closure member, the applicator means having an opening at its lower end and 35 another opening in the applicator means at the crown of the lower surface of the closure member.

3. An applicator comprising a closure member 40 having a concave bottom, a hollow means secured to the closure member within the concave bottom, the hollow means having an opening adjacent its bottom and a second opening adjacent the surface of the concave bottom of the closure member.

4. An applicator comprising a closure member 45 having a concave bottom, a hollow means extending from the closure member within the concave bottom, the hollow means having an opening adjacent its bottom and a second opening at the surface of the concave bottom of the closure member, the hollow means comprising telescoping sections, one within another.

5. An applicator comprising a closure member, a hollow means extending from the bottom of the closure member, the hollow means having an 55 opening adjacent its bottom and a second opening at the surface of the bottom of the closure member, the hollow means comprising telescoping sections, one within the other.

ORESTE R. SCIOSCIA.
